UNITED STATES PATENT OFFICE.

HARRY B. SAWYER, OF OGDEN, UTAH, ASSIGNOR OF ONE-FIFTH TO F. W. BLAIRE, OF OGDEN, UTAH, AND ONE-FIFTH TO DAVID ATHAY, OF SALT LAKE CITY, UTAH.

HITCHING APPLIANCE.

1,145,849.

Specification of Letters Patent.

Patented July 6, 1915.

Application filed July 3, 1914. Serial No. 848,836.

To all whom it may concern:

Be it known that I, HARRY B. SAWYER, a citizen of the United States, residing at Ogden, in the county of Weber and State 5 of Utah, have invented certain new and useful Improvements in Hitching Appliances; and I do hereby declare the following to be a full, clear, and exact description of the invention, such as will enable others 10 skilled in the art to which it appertains to make and use the same.

My invention relates to improvements in hitching devices, and in particular to devices adapted to be attached to a vehicle 15 wheel in such manner that a rope or strap can be run from my device to the check-rein, so that upon the starting of the horse and the consequent rotation of the wheel the horse's head will be jerked backward, there- 20 by stopping the horse.

The main object in my invention is to provide a device that is simple in construction, easily attachable to the wheel of a wagon and accurate in operation.

25 Another object in my invention is to provide a device that will compensate for any wear and tear of the parts that are in frictional engagement with other parts. And still another object of my invention is to 30 provide a device that will operate instantly upon a minimum degree of movement.

With these and other objects in view to be developed I shall now proceed to describe my invention in connection with the accompanying drawings in which, a preferred 35 form is shown, but I desire to be understood that I do not wish to be limited to the form of structure shown, but claim all possible modifications within the scope of the 40 claim appended hereto.

Similar characters of reference refer to similar parts throughout the drawings, in which,

Figure 1, is a transverse sectional view of 45 my device, and, Fig. 2, is a sectional view along the line 2—2 of Fig. 1.

In Fig. 2 of the drawings, 1 is the hub of my device, composed of a metallic ring, having around the central portion of the periphery thereof, a number of indentations 50 or recesses 2, forming therebetween lugs 3. Mounted upon the periphery of my hub is a pair of collars 4 and 5 of matching contour and adapted to be mounted upon the periphery of the ring 1 at the point where 55

the indentations 2 and lugs 3 begin, as plainly shown as at 6 and 7 of Fig. 1. These collars are suitably spaced apart by means of a ring 8, preferably of wood, suitable bolts or other suitable fastening device 9, 60 transversely running through the collars and wooden ring to attach them in proper position.

At suitable intervals in the ring 8, are recesses 10 and indented slots 11 and 12, 65 said indented slots 11 and 12 being connected by a groove 13. Mounted in this groove is a metallic member 14, the ends of which, as at 15 and 16, are bent to seat and play in the indentations 11 and 12, and the 70 part 14 being curved to snugly seat over the lugs 3, previously described. A spring 17 is mounted in the recess 10 to press the metallic member 14 against the lugs 3, and consequently to retain the wooden ring 8, 75 and attached collars 4 and 5 away from the ring 1, thereby compensating for any play due to wear of frictional parts. Interposed between my recesses 10 are other recesses 18, said recesses running at a tangent from 80 the ring 1. Pivotaly mounted within each of these recesses 18 as at 19, is a dog 20, having a pointed end 21 adapted to engage in the recesses 2 previously mentioned.

Outside of the ring 5, I mount a collar 22, 85 retained in position by bolts 23, as plainly shown in Fig. 1. The function of this collar is to retain the collar 5 and attached parts against lateral play in one direction. A second collar 24 is secured on the ring 1 90 on the opposite side of the ring 4, by bolts 25, this collar holding the ring 4, and attached devices against lateral play in the opposite direction. A plurality of slots 26 in ring 24 parallel to its periphery have 95 restricted portions 27, and enlarged portions 28, to receive bolts 29 to allow of adjustable movement therein, the shanks of the bolts 29 seating in the restricted portions 27, and the heads 30 thereof playing 100 in the enlarged portions 28, of the slots 26. A suitable collar or metallic ring 31 is held upon the opposite end of the bolts 29 by nuts 32, this arrangement enabling the device to be adjustably held upon the spokes 105 of a wheel around the hub thereof. The peripheral portions of the rings 4 and 5 are somewhat flared as at 33 and 34 and at suitable intervals through the flared portion 34 are a plurality of apertures 35, through 110

which, by means of hooks 36, I attach the strap or rope 37 running to the check-rein of the horse.

In operation, the device is attached to the hub of a wheel before mounting it upon the axle. To hold the horse, I mount the hook 36 in one of the apertures 35, the rope 37 being connected at its opposite end to the check-rein of the horse. The instant the horse moves, the wagon wheel rotates and carries around the hitching device which rotation of the hitching device pulls backward on the strap or rope 37, thereby jerking the head of the horse backward, which will instantly bring the horse to a halt, and will permit the horse to back without winding the rope or strap around the ring 8. When the horse moves forward, the rope or strap, positioned between the spreading edges of the collars 4 and 5, is wound around the ring 8. This arrangement allows of instant action as soon as the dogs drop from the lugs 3, into the recesses 2, thereby allowing of but a minimum degree of movement, and my device is easily assembled or de-mounted, and easily taken apart and repaired or partly renewed.

Copies of this patent may be obtained for five cents each, by addressing the "Commissioner of Patents, Washington, D. C."

What I claim as new and desire to claim by Letters Patent, is,

A hitching device comprising a metallic hub provided with alternating lugs and recesses in a row around its periphery, a pair of rings secured upon the periphery upon opposite sides of the row of lugs and recesses, a pair of flat circular collars mounted loosely around the hub, a ring between the collars rigidly secured thereto forming a rotatable ring around the hub between the fixed rings, tangential pawls carried by the rotatable ring and engaging in the recesses between the lugs, metallic members radially movable in the rotatable ring, springs located in radial recesses in said ring yieldingly pressing the metallic members against the peripheral lugs, and means for securing the hub upon the hub of a wheel.

In testimony whereof I have signed my name to this specification in the presence of two subscribing witnesses.

HARRY B. SAWYER.
